UNITED STATES PATENT OFFICE.

JOSEPH REIF, OF HEBRON, INDIANA, ASSIGNOR OF FORTY-FIVE PER CENT TO
FRANCIS E. LING, OF HEBRON, INDIANA.

CAR COUPLER.

Application filed May 1, 1922. Serial No. 557,500.

This invention relates to draft appliances but more particularly to couplers such as are used to connect railway cars and has for its primary object to provide a coupler construction which is simple, durable and effective.

Further objects of my invention are to provide a coupler construction in which the release of either coupler automatically causes both to assume the open position as they are moved apart, to provide a coupler which will readily engage when the draw bars are angularly disposed, to eliminate draft strains on pins or other comparatively frail parts, and in general to provide a new and improved coupler.

The many other objects and advantages will be better understood by reference to the following specification when considered in connection with the accompanying drawings illustrating selected embodiments thereof, in which:

Fig. 1 is a plan view showing the couplers open and disengaged.

Fig. 2 is the same as Fig. 1 except that the couplers are partially engaged.

Fig. 3 is the same as Fig. 1 except that the parts are fully engaged and locked.

Fig. 4 is an end elevation of the coupler with the parts in open or unlocked position.

Fig. 5 is a side elevation of the coupler shown in Fig. 4.

Fig. 6 is a detail elevation of the latch.

Fig. 7 is a central vertical section on the line 7-7 of Fig. 9, showing a modified form of my invention.

Fig. 8 is a horizontal section on the line 8-8 of Fig. 7 but with the parts in closed or locked position, and

Fig. 9 is a plan view of the modified form of my invention shown in Fig. 7.

Referring to the drawings, Figs. 1 to 3 show two draw heads A but as these are identical in construction, only one will be described in detail for this description will apply to both. The draw head A is preferably formed of a casting on the outer end of the draw bar B attached to the car in the usual manner. Forwardly extending sides 16 and 17 on the draw head form the socket 18 to admit the corresponding arm 16 of the opposite draw head. A knuckle 19 is pivotally mounted on the vertically disposed pin 20 in the side 16 and the rounded outer end 22 of this side substantially fits in the

correspondingly rounded socket in the knuckle. The tail 23 of the knuckle rests in the socket 24 in this side when the knuckle is in the closed or locked position (Fig. 3). The shoulder 25 on the knuckle acts against the opposing shoulder 26 on the side 16 in this position to resist the pull of the opposite draw bar. This is particularly advantageous as it removes all draft strain from the pin 20.

A spring-pressed plunger 27 in the unlocked position of the coupler projects forwardly into the socket or space 18 and its rear portion extends into the socket 28 in the draw bar. The outer portion of this socket 28 is conical in shape to permit a limited angular movement of the plunger. A spring 29 acts against the annular shoulder 30 in this socket 28 to press the plunger forwardly or outwardly into the position indicated in Fig. 1. A head 31 is formed on the outer end of this plunger to contact with the knuckle 19 on the opposing draw bar as the couplers are moving into engagement. This head 31 is connected to the end of the tail of the knuckle 19 by the pin 32 projecting through the elongated slot 33 in the head. This form of connection between the head 31 and the knuckle 19 causes a swinging or angular movement of the plunger as the plunger is advanced or retracted, due to the arcuate movement of the pin 32. A latch 34 (Fig. 6) projects downwardly in the vertical slot 35 in the side 17 of the head A and is pivotally mounted therein on the pin 36 extending through the perforation 37 in the latch. The lower portion 38 of this latch projects into the channel or groove 39 extending rearwardly in the inner face of the side 17 of the head A. A recess 40 is formed on the inner face of the portion 38 of the latch and the lateral extension 41 of the plunger head 31 rests in this recess when the plunger is in its forward or extended position (Fig. 1). When the plunger moves rearwardly in the manner which will be presently described, this extension 41 gradually moves out of the recess (Fig. 2) until in its rearward position (Fig. 3) it rests against the shoulder 42 on the latch. This shoulder prevents the rotation of the knuckle 19 so long as the plunger is in its rearward position.

The latch 34 is normally held in the position indicated in Fig. 5 of the drawings by 110

the spring 43. A releasing bar (not shown) or other suitable operating means is connected in the usual manner to the latch 34 at 44 to permit the rear portion thereof to be lifted and to rotate the latch in a counter-clockwise direction (Fig. 5) on the pin 36. This rotation causes the shoulder 42 to be moved rearwardly and to disengage the extension 41 on the plunger, permitting the 10 plunger to swing horizontally into the recess 40 and the knuckle to be released. The opposite draw head may now be withdrawn as the knuckle is free to rotate. The withdrawal of the opposite draw head permits 15 the plunger to extend and the knuckle moves to its open position. The withdrawal of the released knuckle from the opposite draw head permits the plunger in this draw head to extend and to move the knuckle connected thereto into open position (Fig. 1). As 20 soon as the knuckle of the opposite draw head is released and moves out of the recess 18 the plunger head 31 moves outwardly until it clears the shoulder 42 and then is permitted to move laterally into the recess 25 40. This outward and lateral movement of the plunger causes the knuckle 19 to be rotated on its pivot into open position as indicated in Fig. 1. It is readily evident that 30 the unlocking of either coupler automatically unlocks the opposite coupler so that both couplers always are in their open or unlocked position when disengaged. The couplers automatically engage and lock when 35 brought together.

One of the particularly advantageous features of the present invention is the wide mouth which is provided. This enables the couplers to readily engage even though the 40 draw bars are angularly disposed as is often the case when the cars are upon a curved track or upon different grades.

When the couplers are moved to engagement the rounded outer end of each knuckle 45 19 strikes the face of the plunger on the opposite drawhead and forces the plunger rearwardly. The rearward movement of each plunger causes the knuckle attached thereto to be rotated about its pivotal connection into interlocking engagement with the knuckle on the opposite drawhead. Fig. 1 shows the position of the parts just before the drawheads come into engagement. Fig. 2 shows the position of the parts when the 50 55 interlocking is partially completed. In this position it should be noted that the extension 41 on the plunger head 31 is just riding out of the recess 40 of the latch. The continued rearward movement of this extension 60 causes the lower portion of the latch to

swing rearwardly or in a counter-clockwise direction (Fig. 5) until the knuckle has drawn the plunger inwardly sufficiently to withdraw the extension 41 from the recess 40 and permit the lower portion of the latch 65 to be forced forwardly by the spring 43, bringing the shoulder 42 opposite the end of the extension in locked position (Fig. 3). The extension then prevents the rotation of the knuckle and the pull of the draw bars 70 is taken up by the shoulders 25 and 26 in the manner described.

A modified form of the invention is shown in Figs. 7 to 9 in which the spring-pressed plunger 50 moves rearwardly in substantially a straight line instead of in a curved path. A latch or pin 51 drops between the plunger and the end of the tail 52 of the knuckle 53 when the plunger has reached its rearmost position (Fig. 8) to prevent the 80 rotation of the knuckle. The knuckle in this form of coupler is not connected to the plunger but is rotated by the flange 54 on the plunger acting through the lower portion of the latch during the rearward movement of 85 the plunger. The latch is connected to the draw head by a pin 55 passing through the elongated slot 56 in the latch. This form of connection permits a swinging movement of the latch during the rearward travel of the 90 plunger and a longitudinal sliding movement at the completion of such travel. The latch is raised by suitable operating means to release the coupler. This form of coupler automatically opens in the same manner as 95 the previous embodiment.

I am aware that many changes may be made in the construction and arrangement of parts without departing from the spirit of my invention, and I reserve the right to 100 make all such as fairly fall within the scope of the following claims.

I claim as my invention:

1. A car coupler comprising a draw head, a knuckle revoluble in said head, a plunger connected to said knuckle so as to control the movement thereof and a latch adapted to engage a part of said plunger so as to prevent uncoupling movement thereof whereby said plunger holds said knuckle against turning. 110

2. A car coupler comprising a draw head, a knuckle revolvably mounted in said head, a spring-pressed plunger pivotally connected to said knuckle, and a latch engaging said plunger to cause said plunger to prevent the rotation of said knuckle when said plunger is held in its retracted position by an opposing coupler. 115

JOSEPH REIF.
